UNITED STATES PATENT OFFICE.

KARL W. KLOSE, OF SENECA, KANSAS.

BRICK-KILN.

1,138,387.

Specification of Letters Patent.

Patented May 4, 1915.

Application filed August 27, 1914. Serial No. 858,926.

To all whom it may concern:

Be it known that I, KARL W. KLOSE, a citizen of the United States, residing at Seneca, in the county of Nemaha and State 5 of Kansas, have invented a certain new and useful Improvement in Brick-Kilns, of which the following is a full, clear, and exact description, reference being had to the accompanying drawings.

10 This invention relates to improvements in brick kiln construction, particularly to the type known as continuous tunnel kilns.

An object is to provide a continuous open top kiln, in which the bricks may be very 15 conveniently handled, both in loading and removal.

Another object is to provide an efficient arrangement of the flues, whereby the fuel may be most economically burned by using 20 air heated in passing through the fired ware and by which the course of the hot resultant gases may be regulated to bring them through the fresh set ware.

Another object is the prevention of injury 25 to the brick or tile, due to the condensation of the gases causing a deposit on the brick.

Another object is to so arrange the sides and flues of the kiln that the whole kiln may 30 be conveniently located below ground, the top being simply plated over with earth—on the ground level.

The invention comprising the means by which I accomplish the above objects, is 35 hereinafter more fully described in connection with a preferred embodiment thereof illustrated in the drawings.

In the drawings, Figure 1 is a vertical transverse section showing a suitable roof 40 and a conveying hoist for the brick; Fig. 2 is a vertical longitudinal section of the same; Fig. 3 is a plan of the fire chambers, showing the arrangement of the flues; Fig. 4 is a perspective view of the fire chambers 45 showing them filled, as when in operation.

In the embodiment shown in the drawings, there are two parallel fire chambers 5 and 6. These chambers having a suitable floor 7, preferably of packed earth, extending 50 underneath both chambers and under vertical side walls 8 and 9 which have their tops substantially even with the surface of the ground. The ends of these chambers are closed by walls 10 and 11, 12 and 13, also 55 coming even with the surface of the ground and resting on the floor 7. The two cham-

bers are divided by a comparatively thick wall 15 having a hollow interior 17, extending throughout its length and forming the main smoke flue. This flue 17 is closed at 60 one end, at 18, and opens at the other end into a passage 19 leading to the small chamber 20 adjacent the ends of the fire chambers. This chamber 20 is surrounded by walls 21, which may be the foundation for a chimney, 65 acting to produce a draft through the flue 17, or may contain a suitable blower 22, used to produce the draft through the passage 19 and the flue 17.

In operation, the fire chambers are piled 70 full of brick, which are so arranged that they leave temporary longitudinal flues 25 (Fig. 4), adjacent the bottom of the chambers. Around and above these flues the bricks are separated allowing space for the 75 passage of the air and gases. At the top two layers of brick are piled tightly together, and sand or earth is spread over them to a thickness of about one inch or more, thus transforming each chamber into a temporary 80 closed tunnel. The air and gases are led in a circuitous course from the place where the bricks are being taken out, (as at 26 in Fig. 4) to the end of the chamber, through the flues 25 to openings 28, leading 85 into a transverse flue 29, in the end wall, and through other openings 28 in the end wall of the other chamber. The air is led through this chamber, feeding the fire, and the gases resultant from the fire are led through openings 30 in the end walls 11 into a flue 32, back into the adjacent end of the chamber 6, and thence to a point where they are drawn 90 off adjacent the end 35 of the pile of brick in the chamber, which is the point where 95 the green bricks are being put in. In piling the bricks, they are so arranged that vertical openings are left leading from the top of the bricks to the temporary flues 25. The top of these openings are closed by removable plugs, indicated at 36 in Fig. 4. The fuel is supplied to the fire in small quantities through these vertical openings by removing the plugs.

At substantially the central portion of 105 the sides of the central wall 17, are flues 38 leading into the wall and then upwardly, and opening at the top thereof. Similar flues also designated 38, pass through the walls 8 and 9 and then upwardly, to the top 110 of the ground. These flues are arranged at intervals throughout the length of the walls.

Just outside of the walls 8 and 9 and beneath the surface of the ground, are passages 40 and 41, respectively, connected by transverse passages 44 and 45 adjacent the end walls of the chambers, forming a passage 5 entirely around the two chambers 5 and 6. The longitudinal passages 40 and 41 have openings 46 opposite the openings of the top of the flues 38 in the side walls 8 and 9. 10 These passages are adapted to be connected with the side walls by removable U-shaped pipes 48^a and 48^b. Adjacent the junction of the passage 44 with the passage 41, and adjacent the junction of the passages 40 and 45, are provided suitable dampers 50 adapted to open and close these passages. The main smoke flue 17 has openings 52 through the top of the wall 15, opposite the openings of the flues 38, and adapted to be 15 connected therewith by other U-shaped pipes 48. 20

In operation the bricks are piled, as above described, in the chambers to a height substantially equal to the height of the side walls, leaving the temporary flues or passages 25 extending longitudinally of the chambers and registering at their ends with the openings 28 and 30, and the fuel is supplied through the vertical passages, closed 30 by the plugs 36. The chambers are thus filled with brick, except a space where the baked ware is being taken out and the green ware put in. The removing of the baked brick at the forward side of this space and 35 the loading of green brick at the rear side of the space, is a continuous process. The open space thus moves along one chamber to the end thereof, then is partly in each chamber, and then travels throughout the 40 other chamber, and so on, continuously. At the same time, the fire is kept at a region which is approximately midway between the points where the green ware is put in and the finished ware taken out by supplying fuel at a proper distance ahead of the point 45 of the removing of the bricks.

Referring to Fig. 4, the wall 26 represents the place where the bricks are being taken out, and air passing through the 50 bricks toward the fire acts to cool them before they are taken out, cooling the still warmer bricks adjacent thereto and passing onto the end of the chamber, through the openings 28 and the flue 29 into the bricks 55 in the other chamber, cooling these bricks somewhat. At the same time, the air is highly heated by them, so that the fire is fed by very hot air. From the fire the resultant gases pass on through the green ware, heating 60 it almost to incandescence adjacent the fire, and warming the bricks in its path, passing through the passages 30 and 32 into the other chamber, and, some distance before reaching the wall 35, through flues 38 65 and through the U-shaped connections 48.

These gases having warmed each section of the brick through which they have passed, rise in the chimney connected with the end of the main flue 17, or, if a blower (as indicated at 22) is used, the gases may be 70 thereby forcibly drawn from the flue 17.

In order to prevent the gases escaping through the open end of the wall 35, and at the same time obviate the necessity of using a series of permanent transverse walls, 75 I avail myself of the common practice in continuous tunnel kilns, namely, after a certain section of brick has been put in—say the amount ordinarily put in in a day—its wall is entirely covered with paper and the next 80 section of brick is piled against the paper. This prevents the draft entering at the wrong place or passing out in the wrong direction. When the next section of brick, however, is piled in place and another wall 85 of paper is pasted over the end of the section, the fire will have advanced close enough to the first wall so that the hot gases coming in contact with the paper will be sufficient to burn it, and thus pass through 90 into the last inclosed section of green brick. After each paper wall has been applied, and the last one before it has burned, the connections 48 adjacent that wall are moved forward a distance equal to the section of 95 brick last put in, thus causing the gases to be drawn through the section of green brick.

In driving out the hygroscopic moisture of the bricks or "water-smoking" them, it is the common practice to heat them with the 100 hot products of combustion from the fire. This is liable to cause an undesirable discoloration or spotting of the bricks. To avoid this I have devised means to drive off all the moisture in the green bricks before the 105 hot products of combustion reach them. This is accomplished by heating the green ware adjacent the wall 35 with air, taken from a point behind the fire and shunted around the fire chambers and led back into 110 the bricks at this point and then into the main flue. Referring to Fig. 4; air which is heated by passing over the hot bricks up to a point adjacent the fire is taken through flues 38 and U-shaped connections 48^a into 115 the passage 40, through the passages 45 and 41, and then into the other fire chamber 3, through pipes 48^b where it heats the green ware until the moisture is driven off from it, and then is taken off through flues 38 and 120 U-shaped connections 48 into the main smoke flue. In this manner the hot air which contains none of the products of combustion, is passed entirely around the fire and the path of the products of combustion, 125 and is used for water-smoking the brick before the pipes 48 are moved forward (after putting in the next section of brick) bringing the products of combustion through them. The water smoking is thus com- 130

pleted before the products of combustion reach the ware, and undesirable discoloring and spotting of the brick by such products is avoided.

5 When the position of the fire is such that it is desired to bring the hot gases around the ends of the two chambers, I open the adjacent damper 50 in this side passage and close the other, thus insuring the proper direction of the draft to bring the hot gases around the nearest end. The openings of the flues 38 and the openings 46, not occupied by the pipes 48, are normally closed by suitable removable plugs, indicated at 54,

15 Figs. 1 and 4.

The entrance openings of the flues 38 being midway between the top and bottom of the side walls, provide for the heat of the gases coming from the fire more evenly drying the bricks, adjacent the point where the gases escape into the main flue 17, than as though the openings were near the bottom or near the top of the walls. This is because, at the point adjacent the paper wall 25 where the gases are being drawn out of the chamber, they approach these openings in an approximately arcual path, leaving a portion of the chamber, at the corners, in which the brick are not in such intimate contact with the heated gases, and thus do not get the benefit of the full drying effect of these gases just before they enter the main flue. If the openings to these flues are near the top of the side walls, this unheated portion 30 of the chamber is much larger at the bottom, or, if the openings are nearer the bottom, it is correspondingly large at the top, and the area or volume of this unheated portion is much greater than when it is divided 35 by placing the openings at the middle portion of the walls.

Referring to Figs. 1 and 2; 60 indicates the roof, 61 and 62 the side walls, and 64 and 65 the end walls of the superstructure 45 or housing constructed over the kiln. 66 indicates a floor above the kiln which may be used for drying the green bricks. The heat from the kiln beneath, causes the brick to be much more quickly dried than when merely 50 exposed to the atmosphere. Suspended beneath this floor 66 and running longitudinally over the center of each fire chamber, are I-beams 67, adapted to support cars 68, for a hoist 70, to which are attached suitable 55 brick carriers, indicated at 72, by which the brick may be conveniently put into and taken from the fire chambers. These I-beams may extend outside of one of the end walls, as at 73, allowing the carriers to be 60 conveniently brought to vehicles for transporting the brick.

Having thus described my invention, what I claim is:

1. A continuous kiln having a bottom, 65 side walls and an open top, a series of individual flues in a side wall opening at the top, a continuous horizontal flue adjacent thereto having upward openings, and means for connecting selectively individual flues with adjacent openings of the continuous flue.

2. A continuous kiln having a bottom and side walls and an open top, a main flue in one of the walls having upward openings, individual upright flues in such wall starting from the face of the wall and terminating at the top and adapted to be selectively connected with the main flue.

3. A continuous kiln below ground, having a bottom and side walls forming an open top the full width of the kiln, a main flue having series of upward openings, and a series of individual flues in the side walls opening upwardly at the top of the ground.

4. A continuous kiln comprising parallel fire chambers having a bottom and side walls and a central partition between the chambers having a main flue, openings leading upwardly from the main flue to the top of the partition, flues in the partition leading upwardly and opening at the top thereof, and means for connecting these openings with the openings of the main flue.

5. A continuous kiln comprising a chamber having a bottom and side walls, a main flue on one side of the chamber and an auxiliary flue on the other, two sets of individual upward flues located in the respective side walls of the kiln, and means adapted to connect selected individual flues with corresponding openings in the adjacent main and auxiliary flues respectively.

6. A continuous kiln having a bottom and side walls the top of which are adjacent the surface of the ground, a main flue, upward flues in the side walls, and a movable connection adapted to connect various of the upward flues with the main flues.

7. A continuous kiln having a bottom and side walls, a series of flues in the side walls opening upwardly, and a passage adjacent said walls having openings corresponding to the openings of said flues, and movable means adapted to connect the openings of said flues with the openings of said passage.

8. A continuous kiln having a bottom and side walls substantially even with the top of the ground, flues opening upwardly and having entrance openings substantially half-way up the wall, a longitudinal passage adjacent the wall and having openings opposite the openings of the flues, movable means adapted to connect various of said openings with the flues, and a main smoke flue for the kiln.

9. A continuous kiln comprising parallel fire chambers each having a bottom and side walls, a central partition having a main flue therein and openings leading upwardly from

the main flue to the top of the partition, a series of flues in the partition extending upwardly and opening at the top thereof, a series of flues opening into the side walls and extending upwardly and opening at the top of the ground, a passage adjacent said side walls having upward openings, means for connecting various of these openings with the upward flues opening into the side walls, and means for connecting the openings of the main flue with the upwardly extending flues in the partition.

10. A continuous kiln having two parallel chambers having bottom and side walls, said side walls being below ground and having their tops substantially even with the surface of the ground, an intermediate partition having a longitudinal draft flue therein, upwardly opening flues occurring at intervals throughout the length of the side walls and the partition, upward openings in the top of the partition leading to the draft flue, removable means adapted to connect various of said openings with the adjacent flues.

25. 11. A continuous kiln comprising longitudinal parallel fire chambers having a bottom, side and end walls, a dividing partition, a main draft flue in this partition having openings in the top of the partition, flues in this partition having their entrance openings intermediate of the top and bottom thereof leading upwardly and opening at the top of the partition, means for connecting the openings of these flues with the main flue, and transverse flues adjacent the ends of each chamber and openings from these flues into the adjacent ends of the chambers.

40. 12. In a continuous kiln, the combination of a pair of longitudinal parallel fire chambers having bottom, side and end walls, said walls coming even with the top of the ground, a dividing partition between the two chambers, a main draft flue in said partition having openings from the top of the partition into the flue, flues in said partition having their entrance openings intermediate of the top and bottom and their exit openings at the top thereof, flues in said side walls having their entrance openings intermediate the top and bottom thereof and their exit openings at the top of the ground, a passage extending around the side and end walls adjacent thereto and beneath the surface of the ground having openings adjacent

the side walls and opposite the flue openings, removable means adapted to connect the various openings of the main flue with the adjacent flue openings in the partition and the exit openings of the flues leading through side walls with the adjacent passages.

13. A continuous kiln having a bottom and side walls, individual flues located in the side walls and starting from the face of the wall and having openings at the top, and longitudinal passages having a series of openings adjacent to the openings of said individual flues, and adapted to be connected therewith selectively.

70 14. A continuous kiln having a bottom and side walls, a series of individual flues located in the side walls and, having an entrance substantially half way up the wall and terminating at the top of the wall, a horizontal flue having a series of openings adjacent to the top openings of the individual flues, and means for connecting the top openings of the individual flues with openings of the horizontal flue.

80 15. A continuous kiln having a bottom and upright side walls, individual flues located in one of such side walls and each consisting of a passageway which extends substantially horizontally from the face of the wall inwardly and then turns upwardly substantially vertically to the top of the wall, an adjacent horizontal flue extending past a plurality of the individual flues, said horizontal flue having upward openings adjacent to the individual flues, and means for connecting such upward openings with the individual flues.

85 16. A continuous kiln having two parallel chambers separated by a partition wall, a main horizontal flue located centrally in such partition wall, a series of individual flues located in said partition wall on opposite sides of the main flue, said individual flues having openings into the kiln chambers and openings at the top, said main flue having a series of openings at the top adapted to be connected with the individual flues.

90 100 In testimony whereof, I hereunto affix my signature in the presence of two witnesses.
